UNITED STATES PATENT OFFICE.

FRANK PARDEE, JR., OF HAZLETON, PENNSYLVANIA, ASSIGNOR TO ANTHRACITE SEPARATOR COMPANY, OF HAZLETON, PENNSYLVANIA, A CORPORATION OF PENNSYLVANIA.

TOOL HOLDER.

Application filed March 27, 1925. Serial No. 18,690.

To all whom it may concern:

Be it known that I, FRANK PARDEE, Jr., a citizen of the United States, and a resident of Hazleton, county of Luzerne, and 5 State of Pennsylvania, have invented certain new and useful Improvements in Tool Holders, of which the following is a specification.

This invention relates generally to tool 10 holders and while not limited thereto aims to provide means for releasably locking a punch or similar tool in proper working position in its supporting member. Various embodiments of the invention are shown in 15 the accompanying drawings.

Fig. 1 is a fragmentary elevation with parts shown in section illustrating a gang of punches releasably locked in their holder;

Fig. 2 is an enlarged cross-section on line 20 2—2 of Fig. 1;

Fig. 3 is a magnified view of portions shown in Fig. 2;

Figs. 4 and 5 are sectional details illustrating alternative embodiments of the invention;

Fig. 6 is a horizontal section illustrating an alternative construction having certain advantages over the other devices illustrated;

Fig. 7 is a detail view of a locking member shown in Fig. 6;

Figs. 8, 9 and 10 are details illustrating various forms which the locking pin may take.

Referring in detail to the drawings, 10 represents the ram of a punch press which may be of any known type and reciprocated in the usual manner. 12 represents a platen or bed of such a press and 14 the work 40 which is to be perforated.

In the embodiment of the invention illustrated, I preferably secure a tool holder 16 to the ram by means of bolts 18 or other equivalent securing means. The holder is 45 formed with a plurality of tool sockets 20 adapted to receive the shanks 22 of the punches or other tools 24. The upper surface of the tool holder is grooved as at 26 for the reception of a hardened steel wear 50 plate 28 which bears on the undersurface of the ram 10, this plate being adapted to transmit the thrust from the several punches directly to the ram. The shanks 55 of the punches are approximately the same diameter as the bore of the socket 20 only

sufficient clearance being allowed to permit the insertion of the punches by hand for replacement or sharpening.

For locking the punches within their respective sockets of the tool holder, I provide means which can be easily manipulated to permit the removal and insertion of the tools. The locking means may take various forms certain of which are illustrated in detail.

In the form of locking device illustrated in Figs. 1 to 3 inclusive, the shank of each punch is formed with a notch 30 the upper portion 32 of which is of arcuate contour.

I provide a locking pin 34 which is journaled in a substantially circular opening or bore 36 formed in the tool holder 16. This opening preferably extends at right angles to the axis of the tool socket 20 and intersects said socket.

The locking pin 34 for the greater portion of its length is cut away, for example, as indicated by the line 38 in Fig. 3, so as to form a locking portion of substantially semi-circular cross-section. As thus formed, it is apparent that by turning

the pin on its axis the upper corner 40 can be caused to enter the notch 30 of the tool, thus preventing the same from being withdrawn. The locking pin is provided with a handle 42 which as shown in Fig. 2 is adapted to project downwardly in a vertical line when the corner 40 is within the notch 30. This serves to indicate to the operator that the punches are locked. Furthermore, the weight of the handle tends to

keep the locking pin in locked position. Reference to Fig. 3 will show that a portion 44 of the locking pin is ground off to provide a slight clearance with respect to the

arcuate face 32 of the notch in the punch. By so forming the parts the upper surface of the locking pin can be utilized to act as a cam to wedge or force the punch upwardly and thus firmly seat it in contact with the wear plate 28. Instead of entirely cutting away half of the locking pin as shown at 38 in Figs. 1 to 3 and 10 this locking member may be cut away only at intervals indicated, for example, at 38' in Fig. 8 which spaces, of course, will be opposite to the punches to be locked. An advantage of the type of locking bar shown in Figs. 1 to 3 and 8 is that there is no tendency to shear the pin on the downward stroke of the

punch in case the punch is not seated tightly

100

110

against the bolster. Because of the inclination of the flat surface or cut away portion 38, any relative movement between the punch and its holder caused by the punch 5 striking the work and taking up clearance between the top of the punch and the wear plate 28, will merely tend to rotate the locking pin in a direction tending to release the punch from the lock. Such movement will 10 be indicated by the position of the handle 42 and will call the attention of the operator to the fact that some of the punches are loose.

In Fig. 4, I have shown an alternative 15 embodiment of the invention including a plain cylindrical pin 46 located in a seat 36 formed in the tool holder and adapted to engage a substantially semi-circular notch 30 formed in the punch shank 22.

20 In Fig. 5, I have shown a slightly modified arrangement in which the shank 22 of the punch is provided with an annular groove 31 with which the locking pin 48 is adapted to interfit. With this arrangement 25 it will be understood that the punch can be turned relatively to its holder, whereas, in the forms previously described the locking pin will prevent such turning movement. In the forms of lock shown in Figs. 30 4 and 5, I may use either a plain cylindrical pin or if desired I can use a tapered pin as illustrated in Fig. 9. The tapered pin has the advantage that as the notch becomes enlarged due to wear the punch can be seated 35 against the wear plate by merely tapping the pin so as to wedge the parts firmly in contact with one another.

The form of the invention shown in Fig. 40 6 is particularly well suited for use in gang punches. Such punches frequently are arranged in parallel rows. This figure shows two such rows with the punches in one row staggered or offset with respect to those in the adjacent row. In such gang punches, 45 I propose to use a single locking pin to serve all of the punches in two separate rows. As shown in the drawing the tool holder 16 is formed with a transverse bore 50 which intersects the sockets 20 in which 50 the several punches are seated. Each of the punches are formed with a notch such, for example, as illustrated in Fig. 4 and a cylindrical portion of the locking pin 52 normally dwells within the notch of each tool. 55 The locking pin itself is provided with a number of notches indicated at 54, these being of substantially the same curvature as the periphery of the punch shanks 22. The spacing between the notches corresponds to the spacing between the punches 60 in each row. As thus arranged a slight end-wise movement of the locking pin 52 will bring the notches thereof opposite the punch shanks and when they are so aligned, of course, the punches can be readily removed.

Instead of releasing the punches by an end-wise movement of the locking pin it will be appreciated that I can also release the punches by turning the locking pin 180°. Such turning movement will bring the 70 notches of the locking pin into register with the punches and, therefore, permit their removal. For preventing accidental longitudinal movement or turning movement of the locking pin 52 I provide a set screw 54 75 threaded through a lug 55 of the punch holder which is adapted to be seated in depressions 56, 58 or 60 of the locking pin according to the setting desired.

Though I have described with great particularity the structure details of the various embodiments of the invention illustrated, it is not to be construed that I am limited thereto as various modifications and substitution of equivalents may be made by those skilled in the art without departing from the invention as defined in the appended claims.

What I claim is:—

1. In combination with a notched tool, a holder therefor and a locking member arranged for engagement with the notch of said tool, said member having a portion of such cross-section that it will release the tool when turned relatively in said holder. 90
2. In combination with a notched tool, a holder therefor and locking means arranged for engagement with the notch of said tool and adapted to release the tool when turned relatively in said holder and to indicate whether or not the last named means is in locking engagement with the tool. 100
3. In combination with a notched tool, a holder therefor and a member normally locking the tool in place, said member having an interrupted portion which when the member is set at a predetermined position will permit the removal of the tool from the holder. 105
4. In combination with a notched tool, a holder therefor and a rotatably mounted locking member having a portion of non-circular cross-section adapted to be turned to a position to release the tool. 110
5. In combination with a notched tool, a holder therefor and a locking member pivotally mounted in said holder and having a portion which when said member is turned exerts a force tending to hold said tool rigidly in said holder. 115
6. In a punch press, a multiplicity of notched punches arranged in gangs, a holder for said punches, and a single locking pin mounted for coaction with at least, one gang of punches. 120
7. In a punch press, a multiplicity of notched punches arranged in gangs, a holder for said punches, and a single locking pin mounted for coaction with at least one gang of punches, said pin normally preventing 125

the removal of the punches and being notched and adapted to be moved into register with the punches to permit their removal.

5. 8. In a punch press, a multiplicity of notched punches arranged in parallel rows, a holder for said punches and a single locking member seated in the holder normally

locking the punches in adjacent rows and being cut away and adapted to be moved 10 into register with the punches to permit their removal.

In witness whereof, I have hereunto signed my name.

FRANK PARDEE, Jr.
